NEWSPAPER VENDING MACHINE

Jacob Burck, 921 Castlewood Terrace,
Chicago, Ill. 60640

Filed Jan. 6, 1975, Ser. No. 538,547

Term of patent 14 years

Int. Cl. D20—01

U.S. Cl. D52—3 R

FIG. 1

FIG. 2

FIG. 3

FIG. 4

FIG. 6

FIG. 1 is a left front perspective view of a newspaper vending machine showing my new design;

FIG. 2 is a right rear perspective view thereof;

FIG. 3 is a top plan view thereof;

FIG. 4 is a left front perspective view of another embodiment of my new design of FIG. 1, wherein the top display frame is adapted to receive vertical format newspapers;

FIG. 5 is a right rear perspective view of FIG. 4; and FIG. 6 is a top plan view of FIG. 4.

Des. 242,381
